CLAIM

The ornamental design for combined note pad and holder, therefor as shown.

DESCRIPTION

FIG. 1 is a front elevational view of a combined note pad and holder therefor showing my new design;

FIG. 2 is a side elevational view thereof, the undisclosed side being a mirror image;

FIG. 3 is a top plan view thereof;

FIG. 4 is a bottom plan view thereof; and

FIG. 5 is a rear elevational view thereof.

The broken lines shown in FIG. 1 are for illustrative purposes only and form no part of the claimed design.

FIG. 1

FIG. 2

FIG. 3

FIG. 4

FIG. 5
